UNITED STATES PATENT OFFICE.

ROBERT H. HUMMERT, OF DAYTON, OHIO, ASSIGNOR TO THE S. H. THOMSON MANUFACTURING COMPANY, OF DAYTON, OHIO, A CORPORATION OF OHIO.

RADIATOR CAP.

Application filed November 28, 1924. Serial No. 752,594.

This invention relates to new and useful improvements in radiator caps, and more particularly to a radiator cap of the arm type.

5 It is the principle object of my invention to provide a radiator cap of the arm type that may be turned a sufficient distance beyond its leak-proof position on the radiator neck, to properly aline its arms with the 10 front of the radiator. Many radiator caps of the present form come to a dead thread when their leak-proof position on the radiator neck has been reached, so that they cannot be turned further to properly aline their 15 arms with the front of the radiator. If, for this purpose, they are turned in a reverse direction, their leak-proof connection with their respective radiator necks will be destroyed.

20 My radiator cap, on the other hand, is provided with gasket and spring means which permits it to be freely turned to bring its arms into proper alinement with the front of the radiator while still maintaining its leak-proof connection with the radiator neck. It is not only important that the radiator cap be screwed down tightly upon the radiator neck to prevent the escape of liquid between the threads, but it is extremely desirable from an aesthetic standpoint that its arms, whether they be of the ball, wing or kindred type, shall be parallel with the front of the radiator.

25 In the accompanying drawings Figure 1 is a top plan view of my radiator cap in its alined position, the dotted lines indicating a position of the cap in which the gasket is tight on the radiator neck, and from which it has been turned forwardly to its full line 30 or alined position. Figure 2 is a front elevational view, partly in section, of my improved radiator cap, containing in combination with a cork-copper gasket, a helical spring. Figure 3 is a top plan view of this 35 spring. Figure 4 is a top plan view of the cork-copper gasket. Figure 5 is a front elevational view, partly in section, of my radiator cap employing a curled-spring washer in place of the helical spring. And 40 Figure 6 is a top plan view of the curled-spring washer or compression member.

45 Referring to the accompanying drawings for a detailed description of the various forms of embodiment of my invention, the 50 numeral 1 designates an externally-threaded

filler neck of an automobile radiator 2. The numeral 3 designates a radiator cap formed with two oppositely-disposed radial arms 4, 4 of a design which not only improves the appearance of the cap, but which facilitate 60 the screwing of its tubular, internally-threaded skirt 5 upon the radiator neck 1.

Formed within the cap 3 just above its skirt portion 5, is an annular ledge or shoulder 7 against which is seated a helical annular or garter spring 8 constructed of phosphor-bronze or other material that will not be affected by the liquid in the radiator. (See Figures 2 and 3.) Mounted in the skirt portion 5 of the cap 1 against the 70 spring 8 is an annular gasket 9 which is preferably of the cork-copper type and which is adapted to be brought into tight engagement with the top of the radiator neck 1 to form a leak-proof connection between 75 said neck and the cap when the latter is screwed down upon it.

After the cap 1 has been turned to compress the gasket 9 sufficiently to form a leak-proof connection between the cap and the 80 radiator neck, the arms 4, 4 may stand in the dotted line positions shown in Figure 1, or out of parallelism with the front of the radiator. This being an awkward and unattractive position for them, they may be further turned in the same direction to an alined position with respect to the radiator front, against the compression of the garter spring 8. The radially-yielding property of this spring is sufficient to permit the arms 90 4, 4 to be brought to an alined position from any point where a leak-proof connection between the radiator neck and cap has been effected, without destroying this connection. Thus, by the employment of the spring 8, it is always possible to bring the arms 4, 4 into parallelism with the front of the radiator after a leak-proof connection has been established between the cap and the 95 radiator neck, or, to employ a common expression, after the cap has been screwed home.

Instead of the garter spring 8, a curled-spring washer such as the washer 10 shown in Figures 5 and 6, may be employed to receive the compressive force of the gasket 9 when the cap 3 is screwed down upon the radiator neck 1. The tension of this washer is governed by the number and depth of its undulations or bends, so that the ability 100 105 110

to turn a radiator cap of large diameter beyond its non-leaking point on a radiator neck may be made as great as that of a small cap by increasing the number and depth of

5 the undulations or bends in the washer 10.

I do not wish to be limited to the garter spring or the curled-spring washer as the yielding means to be employed with the gasket to permit a radiator cap to be turned 10 beyond its non-leaking position on a radiator neck for the purpose of bringing the arms of the cap into parallelism with the front of the radiator, since any other suitable means may be employed for this purpose if desired. The means I employ for 15 the above purpose are simple and efficient, and are particularly adapted for use in a one-piece cap.

Furthermore, I do not wish to be limited 20 to an arm cap as the one in which my im-

proved self-aligning means may be employed, since they may be, with equal benefit, used in temperature-indicating and kindred caps without arms.

Having described my invention, I claim: 25

The combination with a fluid container having a filling neck, a cap adapted to be screwed upon the latter and formed with an internal annular ledge, of a gasket within said cap for engagement with the top of 30 said filling neck, and an annular, helical spring within the cap between the annular ledge and the gasket to receive the compressive force of the latter when the cap is screwed down upon the filling neck of the 35 container, for the purpose specified.

In testimony whereof I have hereunto set my hand this 26th day of November, 1924.

ROBERT H. HUMMERT.
